UNITED STATES PATENT OFFICE.

THOMAS GARFIELD COOPER, OF JEFFERSON CITY, MISSOURI.

PRINTING ATTACHMENT FOR PHOTOPRINTING-MACHINES.

1,363,089.

Specification of Letters Patent. Patented Dec. 21, 1920.

Application filed July 16, 1919. Serial No. 311,188.

To all whom it may concern:

Be it known that I, THOMAS G. COOPER, a citizen of the United States, and a resident of Jefferson City, in the county of Cole and State of Missouri, have invented a new and Improved Printing Attachment for Photoprinting-Machines, of which the following is a full, clear, and exact description.

The object of the invention is to provide a new and improved printing attachment for photoprinting machines arranged to automatically print identification characters and other legends on the back of the sensitized printing sheets during the printing thereof, with a view to identify the prints of each particular job, preferably by printing the same number thereon, and also to print the photographer's name on each print. Another object is to enable the operator to set the identifying means for each particular job. Another object is to provide a printing attachment which can be readily applied to an ordinary photoprinting machine as now generally constructed. Another object is to provide a printing attachment which is simple and durable in construction, not liable to get out of order and arranged to require no attention on the part of the operator during the printing of the sheets for a given order.

With these and other objects in view, the invention consists of certain novel construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a sectional side elevation of the printing attachment applied to the hinged door or closing plate of a photoprinting machine, parts being in inking position;

Fig. 2 is a similar view of the same with the parts for setting the numbering wheels in a different position;

Fig. 3 is a sectional side elevation of the same on the line 3—3 of Fig. 6;

Fig. 4 is a front view of the same;

Fig. 5 is a cross section of the same on the line 5—5 of Fig. 6;

Fig. 6 is a plan view of the same with a part shown in section;

Fig. 7 is a side elevation, partly in section, of a photoprinting machine provided with

the improved printing attachment and with the parts shown in printing position; and

Fig. 8 is a similar view of the same with the parts in non-printing position.

The photoprinting machine, illustrated in Figs. 7 and 8, and on which the identification printing device is shown applied, consists essentially of a cabinet 10 provided on top with a glass plate 11 adapted to support a negative 12 on which is superimposed a sheet 13 of printing paper with the sensitized face thereof in contact with the negative 12. The back or the reverse face of the sheet 13 of the printing paper is pressed in firm contact with the negative by a door or plate 14 hinged to a back section 15 provided with arms 16 mounted to swing on a transverse rod 17 attached to brackets 18 fastened to the top of the cabinet 10. The door 14 is provided on top with cam plates 20 having cam slots 21 engaged by a transverse rod 22 held in the free ends of side arms 23 fulcrumed on the rod 17. Links 24 connect the side arms 23 with a pedal 25 mounted on the lower end of the cabinet and under the control of the operator. A spring (not shown) is coiled on the rod 17 and engages the arms 23 to normally hold the latter in uppermost position, as shown in Fig. 8, thus holding the door 14 in open position and with the treadle 25 raised. After the negative 12 and the sheet 13 of printing paper are in position on the glass plate 11, and the operator presses the treadle 25 then the door 14 swings downward to cover the glass plate and press the sheet 13 of printing paper in firm contact with the negative 11. It is understood that the interior of the cabinet is provided with a suitable source of light to insure proper printing of the sheet 13 of printing paper. The under side of the door 14 is provided with the usual felt facing 26.

The door or plate 14 and its facing 26 is provided with registering openings 30 and 31 through which extend a series of numbering wheels, preferably three in number and marked 35, 36 and 37. The numbering wheels 35, 36 and 37 are mounted to turn an enlarged portion 38 of a shaft 39 journaled in a numbering wheel frame 40 provided on the top with a stem 41 slidably engaging a main frame 42 secured on the top of the door 14. A spring 43 is coiled on the stem 41 and is interposed between the top of the frame 40 and the frame 42.

to press the numbering wheel frame downward to engage the bottoms of the numbering wheels 35, 36 and 37 with the back of the print 13 to make a proper impression thereon to provide the print with an identification number, as hereinafter more fully explained. On the upper threaded end of the stem 41 screws a nut 44 resting on the top of the main frame 42 to limit the downward movement of the numbering wheel frame 40. By adjusting the nut 44, the numbering wheel frame 40 can be readily raised or lowered so as to bring the bottom printing faces of the numbering wheels 35, 36 and 37 in proper printing relation with the print 13. The ends of the shaft 39 extend into vertical guideways 45 formed on the main frame 42 to prevent turning of the numbering wheel frame 40 and to guide the same when adjusted in an up and down direction. The nut 44 is locked in place by a set screw 46 after the desired adjustment of the numbering wheel frame 40 has been made. In the opening 31 adjacent the bottom portion of the unit numbering wheel 35 is arranged a printing block 50 glued or otherwise secured to the under side of the door 14 and provided at its bottom with printing characters 51 representing a desired legend such as a photographer's name or the like. Thus when an impression is made, the numbering wheels 35, 36 and 37 print an identification number on the back of the print 13 and the characters 51 print a legend on the said back adjacent the identification number.

In order to automatically ink the printing face of the numbering wheels 35, 36 and 37 and that of the printing block 50, use is made of an inking pad 60 mounted in a holder 61 detachably held by a spring-pressed button 62 on the free end of an L-shaped arm 63 pivoted on a rod 64 held in a bracket 65 attached to the free end of the door 14. Springs 66 are coiled on the rod 64 and engage a crossbar 67 forming part of the arm 63 to normally hold the latter in inking position, that is, with the pad 60 in inking contact with the printing face of the numbering wheels 35, 36 and 37 and the printing face of the block 50, as illustrated in Figs. 1, 2, 3 and 5. On the arm 63 is pivoted a link 70 engaged by a ring 71 held on a chain or other flexible connection 72 extending over a guide wheel 73 mounted to rotate loosely on the rod 64. The flexible connection 72 extends upwardly and rearwardly and its upper end connects by a ring 74 with a collar 75 having a limited turning motion on a crank arm 76 forming part of the rod 22 previously mentioned.

When the several parts are in the position shown in Fig. 8 and the operator presses the treadle 25 then a downward swinging movement is given to the side arms 23

whereby a downward swinging movement is given to the door 14 by the rod 22 traveling in the cam slots 21 thus causing the door to swing faster than the arms 23 whereby a pull is exerted on the flexible connection 72 thereby imparting a swinging motion to the arm 63 to swing the pad 60 out of engagement with the printing faces of the numbering wheels 35, 36 and 37 and the printing face of the block 50, and at the same time the arm 63 and its pad 60 swing out of the path of the door 14 thus allowing the latter to close with the arm 63 and its pad 60 in raised position, as indicated in Fig. 7. When the operator releases the treadle 25 then the door 14 returns to uppermost position and in doing so the pull on the flexible connection 72 is released to allow the spring 66 to swing the arm 63 downward and rearward into inking position with the printing faces of the numbering wheels 35, 36 and 37 and that of the block 50. It is understood that each of the prints of a particular job have printed thereon the same identification number, and for the next job it is desirable to reset the numbering device with a view to print the next following number on the prints of the second job from those of the first job. In order to enable the operator to quickly and conveniently set the numbering wheels, the following arrangement is made: The numbering wheels 35, 36 and 37 are provided with ratchet wheels 80, 81 and 82, each provided with a cut-out portion 83 extending approximately between adjacent teeth, as will be understood by reference to Fig. 3. The ratchet wheels 80, 81 and 82 are adapted to be engaged by pawls 84, 85 and 86 of different length and secured to a pawl carrier 87 mounted to swing on a pivot pin 88 held in a yoke 90 mounted to swing on the shaft 39 as the fulcrum. A spring 91 is coiled on the pivot 88 and bears on the pawl carrier 87 to swing the said carrier toward the ratchet wheels 80, 81 and 82. The pawl carrier 87 is also provided with a handle 92 adapted to be taken hold of by the operator for swinging the pawl carrier away from the ratchet wheels whenever it is desired to do so. The yoke 90 has a limited swinging movement and for this purpose the yoke is provided with a slot 95 (see Figs. 1 and 2) into which project a stop pin 96 held on the numbering wheel frame 40. The yoke 90 is provided on each of the side arms with a single tooth 100 extending between two teeth 101 formed on the free ends of a two-armed lever 102 fulcrumed at 103 on the corresponding side of the numbering wheel frame 40. The lever 102 is provided with a suitable handle 104 and is pressed on by a spring 105 (see Fig. 3) to normally hold the lever 102 and the yoke 90 in the position shown in Fig. 1, that is, with the upper ends of the slots 95 engaging

the pins 96. When it is desired to advance the unit numbering wheel, it is only necessary for the operator to take hold of the handle 104 of the lever 102 and swing the 5 same upward toward the main frame 42 to impart a swinging movement to the yoke 90 whereby the pawl carrier 87 is carried along and the latter's pawl 84 engages the ratchet wheel 80 and turns the same and with it 10 the unit numbering wheel 35 to the next number. When this has been done, the operator releases the handle 104 to allow the spring 105 to return the lever 102 to the position shown in Fig. 1. It is understood 15 that during this return movement of the yoke 90 the pawl 84 glides over the corresponding tooth of the ratchet wheel 80. When the ratchet wheel 80 and consequently the numbering wheel 35 have made a revolution 20 then the pawl 84 extends into the cut-out portion 83 of the ratchet wheel 80, thus allowing the next following pawl 85 to engage its ratchet wheel 81, and when the lever 102 is swung upward by the operator for the next resetting of the numbering 25 wheels then both the unit wheel and the tenth wheel are turned to the next number. The same operation takes place after the numbering wheel 36 has completed a revolution. 30 When this takes place both pawls 84 and 85 extend in the cut-out portion 83 of their respective ratchet wheels 80 and 81, thus allowing the third pawl 86 to move into engagement with its ratchet wheel 82, and 35 when the lever 102 is next swung upward the three numbering wheels are shifted into the next number.

From the foregoing it will be seen that by the arrangement described, the identification 40 characters and other legends are printed on the back of a photoprint during the printing thereof with a view to identify the prints of each particular job. It will also be noticed that the operator in charge of the machine 45 can readily set the numbering device to a following number after the completion of a job. It will further be noticed that the printing attachment can be readily applied to photoprinting machines as now generally 50 constructed without materially altering the construction thereof.

Having thus described my invention, I claim as new and desire to secure by Letters Patent:—

- 55 1. An identification printing device for printing machines, comprising in combination a hinged member and printing elements mounted thereon, an inking device hingedly mounted at one end of said hinged member, means connecting said hinged member and inking device, whereby the inking device is 60 swung on and beneath the hinged member to engage and ink the printing elements during the swinging movement of said hinged member during non-printing movement and
- to non-inking position and out of the path of the hinged member during printing movement.
2. An identification printing device for printing machines, comprising in combination, a hinged member and printing elements mounted on said member and extending through the same, an inking device adapted to ink said printing elements and hingedly mounted on the end of said hinged member, and actuating means connecting said hinged member and inking device and automatically swinging the inking device into active and inactive position during the swinging movement of the hinged member, 70 said inking device being swung on and beneath the hinged member during non-printing movement of the hinged member, and out of the path of the same during printing movement.
3. An identification printing device for printing machines, comprising in combination a hinged member having a felted bottom, identification printing elements attached to said hinged member, said elements comprising printing numbering wheels and a legend printing block, said wheels and block extending through said hinged member with their printing faces approximately 75 flush with the aforesaid felted bottom to print an identification number and legend simultaneously on the back of a sheet held beneath the hinged member upon swinging the hinged member into printing position, and an inking device hingedly mounted on 80 the free end of the hinged member and adapted to ink the entire printing faces of the numbering wheels and pad at the same time during the swinging movement of the hinged member during non-printing movement of the hinged member and out of engagement with said printing faces and out of the path of the hinged member during 85 its movement to printing position.
4. An identification printing device for 90 printing machines, comprising in combination a hinged member having a felted bottom and identification printing elements attached thereto, said elements including printing numbering wheels and a legend 95 printing block, the wheels and block extending with their printing faces approximately flush with the aforesaid felted bottom, and adapted to simultaneously print an identification number and legend on the back of 100 a photo print held in the printing machine at the time upon movement of the hinged member into printing position, an inking pad adapted to ink the active printing faces of the aforesaid wheels and pad 105 by the swinging movement of the hinged member; a spring pressed arm carrying said inking pad and hingedly connected on the free end of hinged member, actuating means 110 connected with said hinged member for 115
- 120
- 125
- 130

swinging the same into and out of printing position, and means connecting said actuating means with the spring pressed arm to swing the inking pad out of engagement 5 with the said wheels and legend block, and out of the path of the said hinged member during its movement to printing position.

5. An identification printing device for printing machines, comprising in combination, a hinged member having an opening therethrough, actuating means for swinging the same into or out of printing position, a frame attached to the upper face of said hinged member, printing numbering wheels 10 journaled in said frame and extending into the opening in the hinged member, the bottoms of said numbering wheels being in printing position relative to a photoprint held in the machine when the hinged member 15 is in printing position, an inking pad adapted to ink the printing faces of said numbering wheels, a spring-pressed arm hingedly mounted to swing on the free end 20 of the hinged member and carrying said

inking pad, and connecting means between 25 said arm and the hinged member actuating means whereby to swing the arm upward on moving the hinged member into printing position.

6. In a photo printing machine in combination, a hinged member, an identifying printing device attached to said member and comprising printing elements, an inking device hingedly mounted on the free end of said hinged member, and interconnecting 30 means between the inking pad and said hinged member whereby said pad is adapted 35 to ink said printing elements at the time the hinged member swings out of printing position and to swing the inking pad out of 40 inking engagement with the printing elements and out of the path of said hinged member during and by its movement to printing position.

Signed at Jefferson City, in the county of Cole and State of Missouri, this 11th day of July, 1919.

THOMAS GARFIELD COOPER.
